CLAIM

The ornamental design for a camera cover as shown and described.

DESCRIPTION

FIG. 1 is a top, front, right side perspective view of a camera cover showing our design, showing the camera cover with surface shading;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof;

FIG. 7 is a bottom plan view thereof;

FIG. 8 is a top, front, right side perspective view of the camera cover of FIGS. 1-7, showing the camera cover without linear surface shading;

FIG. 9 is a front elevation view thereof;

FIG. 10 is a rear elevation view thereof;

FIG. 11 is a right-side elevation view thereof;

FIG. 12 is a left-side elevation view thereof;

FIG. 13 is a top plan view thereof; and,

FIG. 14 is a bottom plan view thereof.

The dashed broken lines represent unclaimed features of the claimed design. All broken form no part of the claimed design.

1 Claim, 14 Drawing Sheets
